United States Patent Office

Des. 198,429
Patented June 16, 1964

198,429

NECKTIE

George M. Hendrix, Box 42, Denver 8, Colo.

Filed Apr. 22, 1963, Ser. No. 74,575

Term of patent 14 years

(Cl. D3—16)

The figure on the drawing is a top plan view of a necktie showing my new design. The necktie is of conventional thickness and the essential features thereof reside in the portions shown in solid lines.

I claim:

The ornamental design for a necktie, as shown and described.
